JOHN F. O'CONNOR, OF CHICAGO, ILLINOIS, ASSIGNOR TO WILLIAM H. MINER, OF CHAZY, NEW YORK.

DRAFT-YOKE FOR RAILWAY-CAR DRAFT-RIGGING.

1,198,755.

Specification of Letters Patent. Patented Sept. 19, 1916.

Application filed July 19, 1916. Serial No. 110,016.

To all whom it may concern:

Be it known that I, JOHN F. O'CONNOR, a citizen of the United States, residing at Chicago, in the county of Cook and State 5 of Illinois, have invented a certain new and useful Improvement in Draft-Yokes for Railway-Car Draft-Rigging, of which the following is a full, clear, concise, and exact description, reference being had to the accompanying drawings, forming a part of 10 this specification.

My invention relates to improvements in draft gear yokes for railway car draft rigging.

15 The object of my invention is to provide an efficient draft yoke having means for readily detaching a draw bar therefrom.

In the drawings forming a part of this specification, Figure 1 is a side elevation, 20 partly in vertical, longitudinal section of a draft yoke embodying my invention. Fig. 2 is a horizontal section on line 2-2 of Fig. 1. Fig. 3 is a front end view of the draft yoke. And Fig. 4 is a perspective 25 view of the rotatable segment.

Referring to the drawings, the numeral 5 indicates the upper limb and 6 the lower limb of the draft yoke. At their rear ends, the said limbs are connected by a preferably 30 integral member 7. The pocket 8 within the yoke is adapted to receive a draft gear in a manner that will be well understood. At its forward end, the yoke is provided with a preferably integral, hollow head 9 35 formed by the upper member 10, which is preferably the integral forward end of the upper limb 5, the side plates 11-11 and the lower plate 12. The lower plate 12 is preferably a forward extension of the lower

40 limb 6 curved downwardly and then upwardly, as clearly illustrated in Fig. 1 of the drawings. The side plates 11 connect the upper and lower limbs of the yoke and are suitably spaced apart laterally to permit the reception within the hollow head 45 of the yoke of the butt 13 of the draw bar 14. The upper portion of the head is provided at its forward end with the inturned gib 15 adapted when the draw bar is in position within the yoke to be engaged by the upper shoulder 16 of the draw bar. The draw bar is likewise provided with the usual 50 lower shoulder 17. The space between the lower face of the gib 15 and the lower plate 12 is sufficient to permit the entry there-

through of the draw bar butt. A member 19, which is preferably integral with the side plates 11, passes transversely of the head near its lower portion, the upper surface thereof being substantially flat and the lower face being suitably curved to form between it and the member 12 a curved channel 20 adapted to receive the similarly curved locking segment 21. The locking segment is of a suitable length to permit its insertion in the channel 20 with the front end 22 thereof in the same plane or below the plane 23 of the floor of the yoke head, formed by the front end of the member 12 and the upper surface of the transverse member 19. When the locking segment is in this position, the draw bar may be inserted in the head until the shoulders thereof are back of the gib 15 and the forward opening 24 of the channel 20. When in this position, the draw bar is lifted until the upper shoulder 16 thereof engages the gib 15 and the locking segment is then rotated in the channel 20 until the forward end thereof is in engagement against the lower shoulder 17 of the draw bar, as shown in Fig. 1 of the drawings. The segment is provided with a groove 25 which, when the segment is in its locking position, registers with a transverse groove 26 in the lower face of the channel 20 and the side plates 11 are suitably apertured as at 27 to permit the insertion of the bolt 28 which passes therethrough and engages within the opposed grooves in the locking segment and in the lower face of the channel, thus holding the locking segment in its locked position. A head 29 at one end of the bolt and a cotter key 30 at its other end prevent the accidental displacement of the bolt. 95

It will be observed that the position of the bolt is such that, in the most usual car constructions, it will be sufficiently beneath the draft sills of the car to permit its ready insertion and removal without the slotting of said draft sills. The side plates on their inner faces near the bottom portion of the head are provided with the upper shoulders 31-31 against which the forward edge 32 of the locking segment engages when in its locked position, thus on forward pull of the draw bar, its connection with the yoke is maintained through the engagement of the upper shoulders against the gib 15 and through the engagement of the lower shoul- 110

ders against the locking segment, which locking segment is held in position by the shoulders 31 and through it is secured within the channel 20.

5. The locking segment 21 is provided with the finger 40, by which the said segment may be manually operated, the said finger riding in the longitudinal slot 41, with which the lower limb 6 of the yoke is 10 provided.

I claim:

1. In a draft yoke, the combination with a hollow head to receive a shouldered draw bar, of a rotatable segment to engage said draw bar and a channel in the yoke head to receive said segment.

2. In a draft yoke for railway cars, a hollow head adapted to receive a draw bar, a curved channel in said head and a rotatable segment operable in said channel, adapted to engage the draw bar to secure the same within the yoke head.

3. In a draft rigging, the combination with a draw bar having shoulders, of a draft yoke having a hollow head to receive the draw bar, the head being provided with fixed means to engage one draw bar shoulder and movable means to engage the other draw bar shoulder, said movable means comprising a rotatable segment and a channel to receive said segment.

4. In a draft rigging for railway cars, the combination with a shouldered draw bar, of a draft yoke having a hollow head to receive the draw bar, the head being provided with a gib to engage one draw bar shoulder and a curved segment to engage the other draw bar shoulder, the head being provided with a channel to receive said curved segment.

5. In a draft rigging for railway cars, the combination with a shouldered draw bar, of a draft yoke having a hollow head, the said head being provided with a gib to engage one draw bar shoulder and a rotatable segment to engage the other draw bar shoulder, the said head being provided with a channel to receive said segment and within which the segment may be moved into unlocking position.

6. In a draft rigging for railway cars, the combination with a shouldered draw bar, of a draft yoke having a hollow head to receive the draw bar, the head being provided with a gib to engage one shoulder of the draw bar and with a rotatable segment to engage the other shoulder of the draw bar, the said head being provided with a channel to receive said segment and being further provided with a bolt to hold said segment in a fixed position within said channel.

7. In a draft rigging for railway cars, the combination of a draw bar with a draft yoke having a hollow head to receive the draw bar, the said head being provided with means to retain the draw bar therein, said means comprising a rotatable segment, a channel within the head to receive said segment, and means for securing said segment in a determined position within said channel.

In witness that I claim the foregoing I have hereunto subscribed my name this 15th day of July, 1916.

JOHN F. O'CONNOR.
